UNITED STATES PATENT OFFICE.

WILLIAM W. DAY, OF WASHINGTON, DISTRICT OF COLUMBIA.

CARD-INDEX BOX.

1,110,748.

Specification of Letters Patent. Patented Sept. 15, 1914.

Application filed April 15, 1913. Serial No. 761,383.

To all whom it may concern:

Be it known that I, WILLIAM W. DAY, a citizen of the United States, residing at Washington, in the District of Columbia, 5 have invented a new and useful Card-Index Box, of which the following is a specification.

My invention relates to new and useful improvements in a card index box and has 10 for its primary object the provision of a box which may be used with the cabinets or stands at present in use.

A further object is the provision of means for holding the cards securely in the box so 15 that they cannot be accidentally displaced.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, can be made within the scope of what is claimed, without 25 departing from the spirit of the invention.

In the drawings:—Figure 1 is a perspective view with parts broken away. Fig. 2 is a longitudinal sectional view. Fig. 3 is a 30 fragmental sectional end view. Fig. 4 is a detail view of one end of the swinging rod. Fig. 5 is a fragmental end view.

In Fig. 1 of the drawings I have shown my invention as applied to a double box but it is to be understood that the invention is 35 particularly adapted for a single box.

In the drawings the numeral 1 indicates the front end of the box, 2 the rear end of the box and 3 the center partition of a double form. It will therefore be noted that one 40 side of the box is open and the cards are adapted to be removed from the open side of the box. I have indicated the cards by the numeral 4 and a rod 5 extends longitudinally across the top of the box and 45 passes through the ends. This rod is secured in position by means of the nut 6. A bow-shaped spring member 7 is mounted on the rod 5 and secured to this spring member is the follower 8 which is adapted to engage 50 the cards. When it is desired to move the follower 8 the ends of the spring member 7 are raised which will allow the rod to pass freely through the opening in the spring member. A groove 9 is formed in the end

of the follower the purpose of which will 55 presently be described.

A rod 10 extends longitudinally across the open side of the box and the front end of this rod is provided with the right angle extension 11 which is adapted to enter an elongated recess 12 formed in the front end 1 of the box. An extension 13 is formed on the right angle extension 11 and passes through the end of the box and a knob 14 is secured on the end of this extension. This 65 knob carries the sleeve 15 and a spring 16 surrounds the extension between the end of the box and the knob. The opposite end of the rod 10 is provided with the right angle extension 17 which is received in the recess 70 18 formed in the rear end of the box and passes through the opening in the end of the box thereby forming a bearing for the rod and formed on the extension 17 is the hooked extension 19 of the shape clearly shown in 75 Fig. 4 and providing the projection 20 adapted to enter a hole 21 formed in the rear end 2 of the box. As clearly shown in Figs. 1 and 2 the recess 18 is of such a depth 80 as to allow the rod to be moved longitudinally. The rod 10 also passes through the groove 9 formed in the end of the follower 8 and provides an additional guide for the follower. The bottom edge of the open side 85 of the box is cut away as shown at 22, the purpose of which will be presently described.

Having fully described the detailed construction of my device it is thought that the operation will be clearly understood.

When the rods 5 and 10 are in the positions shown in Figs. 1 and 2 the cards are securely held in position and cannot be removed. When the cards are to be removed the operator grasps the knob 14, at the same time pressing on the same at which time the 90 rod 10 is moved longitudinally and disengages the extension 11 from the recess 12. The knob is then turned which swings the rod 10 into the position shown in dotted lines in Fig. 3 and it will be seen that the 100 rod will be received in the cut away edge 22. The longitudinal movement of the rod 10 also disengages the projection 20 from the recess 21 formed in the rear end of the box, It will be seen that by constructing a box in 105 this manner the cards do not have to be cut in any manner and thereby any cards may be used.

Having fully described the invention, what I claim as new and desire to secure by Letters Patent is:

1. A card index box open at one side its entire height above the bottom, and a vertically swinging rod extending longitudinally across the open side of the box. 55
2. A card index box open at one side, a rod secured longitudinally across the top of the box, and a vertically swinging rod secured longitudinally across the open side of the box. 60
3. A card index box open at one side, a rod secured longitudinally across the top of the box, a follower operating on said rod, and a vertically swinging rod secured longitudinally along the open side of the box. 65
4. A card index box open at one side, a rod secured longitudinally across the top of the box, a bow-shaped spring member operating on the rod, a follower secured to the spring member, and a vertically swinging rod secured longitudinally along the open side of the box. 70
5. A card index box open at one side, a rod secured longitudinally across the top of the box, a vertically swinging rod secured longitudinally across the open side of the box, and means for locking said rod in position. 75
6. A card index box open at one side, a rod secured longitudinally across the top of the box, a longitudinally movable and vertically swinging rod secured along the open side of the box, and means for locking said rod, said locking means being released by the longitudinal movement of the rod. 80
7. A card index box open at one side and having an elongated recess formed in one end thereof, a rod extending longitudinally across the open side of the box and provided with a right angled extension on each end, and the ends of said extensions passing through the box, and the angled portion of one of said extensions entering the elongated recess. 85
8. A card index open at one side and having an elongated recess formed in one end thereof, a rod extending longitudinally across the open side of the box and provided with a right angle extension on each end, the end of said extensions passing through the ends of the box, the angled portion of one of said extensions entering the elongated recess. 90
9. A card index box open at one side and having an elongated recess formed in one end thereof, a rod extending longitudinally across the open side of the box and provided with a right angle extensions on each end, the ends of the extensions passing through the box, one angle of one of the extensions entering the elongated recess, a knob secured on the end of the rod for moving the rod longitudinally for releasing the extension from the recess and a spring surrounding the extension between the knob and end of the box. 95
10. A card index box open at one side and having an elongated recess in one end and a cut away portion in the opposite end, a rod extending longitudinally across the open side of the box and having right angle extensions, the ends of which pass through the ends of the box and the angled portions being received in the elongated recess and cut away portion, a knob on one end of the rod for moving the same longitudinally and swinging it vertically, and a projection on the opposite end of the rod adapted to enter an opening in the end of the box. 100
11. A card index box open at one side, a rod extending longitudinally across the top of the box, a follower operating on said rod and having a groove formed in one end thereof, a longitudinally movable and vertically swinging rod extending across the open side of the box and adapted to pass through the groove in the follower, and means for locking said rod in position, said means being released by the longitudinal movement of the rod. 105
12. A card index box having a longitudinal central partition, open on the sides, and longitudinally movable and vertically swinging rods extending across the open sides of the box, and means for locking the rods in position, said means being released by the longitudinal movements of the rod. 110

In testimony that I claim the foregoing as my own, I have hereto affixed my signature in the presence of two witnesses.

WILLIAM W. DAY.
